CLAIM

The ornamental design for a HDMI cable head, as shown and described.

DESCRIPTION

FIG. 1 is a top left perspective view of the HDMI cable head; FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Dashed lines do not form a part of the claimed subject matter.
